UNITED STATES PATENT OFFICE.

EVEREST A. BAYLIS, OF EL PASO, TEXAS.

CENTRIFUGAL SEPARATOR.

1,308,271.

Specification of Letters Patent.

Patented July 1, 1919.

Application filed August 23, 1915. Serial No. 46,961.

To all whom it may concern:

Be it known that I, EVEREST A. BAYLIS, a citizen of the United States, residing at El Paso, in the county of El Paso and State of Texas, have invented certain new and useful Improvements in Centrifugal Separators, of which the following is a specification.

This invention relates to improvements in centrifugal separating machines for separating heavier from lighter material by centrifugal force, and particularly to improvements in centrifugal machines of the type disclosed in my prior application Serial No. 846,524, filed June 22, 1914, embodying a plurality of separating drums or receptacles arranged to rotate about a common axis with respect to each other and which are also axially rotatable independently of such common axis upon their own axes at a desired speed or speeds.

The primary object of the invention is to provide a novel and simplified construction of machine of the type specified wherein the drums or receptacles are mounted upon a continuous driving shaft for rotation therewith, and are also rotatable about their own axes through the medium of a novel construction of gearing between the same and the shaft.

A further object of the invention is to provide a centrifugal separating machine in which drums and co-operating separating devices of improved construction are provided for facilitating and increasing the efficiency of separation of materials of different specific gravities and discharging them separately into different receptacles.

A still further object of the invention is to provide means whereby the drums or receptacles may be inclined to different degrees with respect to their centers of rotation to vary their working slope or angle to secure the best results according to the character of the material which is under treatment.

A still further object of the invention is to provide a centrifugal separating machine in which provision is made for the interchangeable use of drums for separating solids of different specific gravity from each other or for separating solids from liquids and clarifying the latter.

With these and other objects in view, the invention consists in the features of con-

struction and combination and arrangement 55 of parts more fully hereinafter described, reference being had to the accompanying drawings, wherein—

Figure 1 is a vertical sectional view of a centrifugal apparatus embodying a preferred form of my invention;

Fig. 2 is a sectional plan view on the line 2—2 of Fig. 1;

Fig. 3 is a fragmentary sectional plan view on the line 3—3 of Fig. 1;

Fig. 4 is a detailed plan view of the eccentric mechanism associated with one of the drums for varying the working angle or slope thereof;

Fig. 5 is a diametric plan view of one of 70 the separating drums or receptacles;

Fig. 6 is a fragmentary perspective view thereof, showing the loop or return portion of the flange or riffle thereof;

Fig. 7 is a view of one of the water supply pipes;

Fig. 8 is a detail section on the line 8—8 of Fig. 1, looking downward;

Fig. 9 is a fragmentary sectional view showing the application of a modified form 80 of separator for separating solids from liquids; and

Fig. 10 is a view of the supporting yoke employed in Fig. 9.

Like characters of reference designate 85 similar parts throughout the different figures of the drawings.

As illustrated, 1 designates a supporting bearing upon the base of the machine, which is in the form of a spider having arms 2 90 radiating from the post bearing 1 and connected by an outer spider rim 3, adapted to be secured to a suitable foundation. Arising from the base are standards or uprights 4 which may be tied and braced in any suitable manner and which are secured to and carry at their upper ends a bearing bracket 5 arranged in axial alinement with the base bearing 1. A continuous shaft 6 is journaled at its lower and upper ends in the respective bearing members 1 and 5 and carries a drive pulley 7 whereby it may be rotated from any suitable source of power. A hollow sleeve or shaft 8 surrounds the shaft 6 at a point immediately above the transverse center 100 thereof and carries a pulley 9 whereby it may be driven independently of the shaft 6 from any suitable source of power, the said

shaft 8 revolving with and about the shaft 6, as will be readily understood.

- Also surrounding the shafts 6 and 8 is a hollow sleeve or shaft 10 which carries a 5 hopper 11 for the reception of the material which is to be supplied to the separating devices. This hopper rotates with the shaft 6, as hereinafter described, and is arranged to receive the material from a superposed chute 10 or conductor 12 carried by the arms 4 of the stationary framework, and to which the pulp or material is conducted from a primary source of supply through a pipe or conductor 13.
- 15 Fixed to the shaft 6 is a collar or head 14, which is thus mounted for rotation with said shaft, and formed in this collar or head is an annular series of openings 15, equal in number to the separating drums or receptacles 16 employed. Each of these drums or receptacles 16, as illustrated in one form of the invention, consists of a vertical cylinder open at its lower end for the discharge of the separated substances and provided at its 25 upper end with a head 17 secured to or provided with a bearing sleeve or collar 18 mounted to revolve with and about a supply pipe or tube 19 fixed to and depending from the hopper 11.
- 30 The supply pipes or tubes 19, which are equal in number to the separating drums, are provided for the discharge of the pulp or material from the hopper to the respective drums, and are provided at their lower ends 35 with laterally bent or curved discharge nozzles 20, extending outwardly and in close proximity to the concentrating or separating surface of the drum. The bearing sleeve 18 is journaled in a suitable type of anti-friction joint member or knuckle 21 which is mounted to tilt within a socket formed by the opening 15, the meeting surfaces of the knuckle and socket wall being segmentally curved so as to adapt the depending separating 40 drum or receptacle 8 to be supported in a perpendicular position or to be tilted at an angle to the perpendicular to vary the slope or inclination of its separating surface, as hereinafter fully described.
- 45 The pulp or material entering the upper portion of each rotary drum or receptacle 8 is discharged against the relatively outer surface of the inner wall of the drum, which wall of the drum is provided with a spiral 50 flange or riffle 22 of just sufficient width or extent of projection to engage and carry the solid matter of the pulp upward in the rotation of the receptacle, which revolves with the shaft 6 in the direction of the arrow 55 shown in Fig. 4, and upon its own axis in the direction of the arrow illustrated in Fig. 2. The upper convolutions of this spiral riffle are connected by a loop or return portion 23, forming a bucket or collecting portion 60 by which the solid material separated from

the lighter material and carried upward to the top of the separator drum will be transferred from the separating to the discharging surface of the wall of the drum, as hereinafter fully described.

Assuming that the material to be treated is a mineral ore, and that the heavy mineral matter contained therein is to be separated from the gangue or tailings, it will be understood that the material discharged from the spout or nozzle 20 will be thrown outward by centrifugal force into engagement with the outer separating or concentrating surface 24 of the inner wall of the drum, which is at the greatest distance from the center of rotation of the drum, and will be picked up and held by the flange or riffle and carried upwardly thereby to the top of the drum in the rotation of said drum, while the lighter tailings or gangue matter 70 separated by centrifugal action from the mineral matter will pass downwardly and discharge through the bottom of the drum. The concentrates or heavy mineral matter thus carried to the top of the drum after 75 being separated from the lighter matter or tailings will be conducted by the loop or return portion 23 to the innermost or discharge surface 25 of the inner wall of the drum, which is closest to the center of rotation of 80 said drum, for discharge as hereinafter explained. It will be evident from the foregoing description that the spiral riffle is pitched to carry the heavy material upward toward the top of the receptacle, assisted by centrifugal action, thus causing the precipitation of the tailings or lighter matter which will fall downward along a line between the axial center and the concentrating or separating 85 surface of the drum.

90 Arranged within each drum is a downwardly and outwardly inclined discharge trough 26, which extends from the top of the drum downwardly through the bottom of the drum. This trough 26 is of concavo-convex form, its convex and concave sides being presented, respectively, toward the concentrating or separating and discharging surfaces 24 and 25 of the drum. The trough is 95 of segmental form in cross section and carries at its upper end a segmental shield or deflector 27, extending on the arc of a circle of greater diameter than the trough body and serving as a partition within the top of the drum between the surfaces mentioned 100 and as an abutment against which the concentrates are directed by centrifugal force in the discharge action. The concentrates or 105 heavy material carried around by the loop or return portion of the riffle from the concentrating to the discharge surface of the drum are dashed by centrifugal force against the deflector 27 and caused to slide by gravity and centrifugal force downward along the inner side of the trough 26 into a concen- 110

trates receptacle 28 having an outlet 29, while the tailings, gangue or lighter material pass downward, as described, between the discharge surface of the drum and the trough and are discharged by centrifugal force into a separate receptacle 30, from which the tailings may be removed in any preferred manner. The respective receptacles 28 and 30 are carried by the base of the machine and are annular in form, as shown, the receptacle 28 being arranged above a lid or cover fixed to the shaft and provided with openings 32 in line with the drums for the passage of the concentrates from said drums to said receptacles.

It will be evident that the pulp to be treated is distributed equally among all of the concentrator or separator drums by the centrifugal motion of the machine, thus maintaining a perfect balance of the machine, and that as the pulp is fed to the machine near the center of the machine very little power is required to put it into motion with the machine and accordingly it is being revolved at the same speed as the machine before it is forced into the cylinders. As the separator drums revolve the air contained in that side of each drum nearest the center of the machine or center of rotation is thrown outward or toward the opposite side of the drum farthest from the center of the machine or center of rotation, thus causing a partial vacuum or decrease of air pressure on the particles of the material contained in the rifled loop or bucket. This decrease of air pressure greatly facilitates the discharge of the heavy particles or concentrates in the bucket, the concentrates being thereby discharged both by centrifugal force and suction against the trough or discharge chute. By thus forming a partial vacuum in each drum another advantage is gained in that the pulp is not only forced into each drum by centrifugal force, in equal proportion to each drum, but feeds thereto under great pressure and drawn in by considerable suction, thus requiring but a comparatively small feed opening, as under these conditions the pulp travels at a very high velocity.

In order to facilitate discharge of the material downwardly along the trough and surface of the receptacle, I may provide means such as a pipe 33 whereby streams of water may be projected into the trough and drum to flush the same and thereby facilitate the discharge of the material. These pipes extend upward through the supply tubes or pipes 18 and communicate with a water reservoir 34 to which leads a water supply pipe 35, which reservoir 34 is provided with an inclined or spiral shelf 36, the reservoir being mounted to rotate with the hopper 11, and the water being conducted by the spiral shelf in such a way as

to prevent its excessive agitation under centrifugal force and secure its even and regular flow to the water supply pipes. It will be understood that the water discharged against the pulp traveling upward toward the collecting surface of the riffle facilitates the separation of the light from the heavier particles by washing away from the heavier particles all the light weight material which may be retained thereby. On account of their moisture coating the heavier particles are further increased in weight to facilitate their separation from the lighter material. The spray or wash water coming in contact with the inclined trough or chute tends, under the combined force of gravity and centrifugal action, to rush downwardly, thus further scouring or washing the heavier particles of any light material that may be carried thereby, and which have not been before discharged, while at the same time facilitating the discharge of the heavier particles themselves along the chute. The means for revolving the drums consists of a crown bevel gear 37 on the sleeve or shaft 8 which meshes with bevel gears 38 upon radial shafts 39 journaled in suitable gear casings upon the head 14, which shafts carry worms 40 meshing with worm gears 41 on the bearing sleeves of the drums, whereby in the operation of the machine the drums will be revolved at a high rate of speed by and with the shaft 6 as a unit, and will be slowly revolved upon their own axes for a feed action of the material therein by the spiral flanges or riffles.

It will be seen from the foregoing description that when the apparatus is set into action and supplied with the pulp or other material to be treated, a rapid and efficient separating action will be secured, and that the discharge of the material may be facilitated by the use of streams of water from the supply pipes whenever desired. It will also be evident that the separating action will be more complete and more rapidly effected, inasmuch as through the described construction of the drum and arrangement of the discharge trough therein the heavier and lighter materials when separated will be kept separated and separately discharged. It will, of course, be understood that the machine may be revolved at greater or less speed, according to the character of the material to be treated and the degree of separation desired. To facilitate the separating action and control the feeding and separatory action of the spiral riffle in the treatment of material carrying tailings or gangue heavier or lighter than the average, I provide means whereby the pitch or slope of each separator drum may be varied to correspondingly vary the working angle of the riffle. As shown in the present instance, the drums extend downward through openings

in a second collar or head 42 fixed to the main shaft 6 and rotate in anti-friction bearings 43, between which and the walls of the openings are interposed cam devices, each 5 consisting of a pair of cam rings 44 and 45, said rings having rack teeth 46 engaged by an adjusting gear 47, which may be manually operated in any suitable manner, whereby the eccentric rings may be turned or rotated 10 in opposite directions to vary the arrangement of their eccentric surfaces, so as to tilt the drum to vary its pitch or slope and, correspondingly, the working pitch or slope of the riffle, as will be readily understood. The 15 surface of the outer ring is segmental in form, and the wall of the opening in the head 42 is of corresponding form, thus forming a ball and socket connection which permits the drum to tilt as and for the purpose 20 described.

The machine is adapted for the use of interchangeable drums for treating various substances, such as for concentrating, as one instance of the separation of solids, as before described, or for separating a solid from a liquid and clarifying the latter. As illustrated in Figs. 9 and 10, I may employ interchangeably with the drums 8 drums 8^a, in the nature of comparatively wide and shallow 25 vessels, each having at its upper end a sloping catch basin 48 to direct the material entering through the supply pipe or tube downwardly and preventing it from flying directly outward by centrifugal force. The 30 material entering the drum falls upon a horizontal baffle or partition plate 49 extending outwardly toward the portion of the surface of the drum farthest from the center of rotation, which shelf conducts the material outwardly toward the periphery of the drum, in which the solid collects, such solid being carried around from the outer separating 35 surface 50 to the inner discharge surface 51 in the rotation of the drum and projected by 40 centrifugal force against the deflecting surface 52 of a discharge trough 53, which may be of the form and construction previously described, whereby the solid matter is directed to an outlet or receptacle 54, while 45 the clarified liquid flows outward through an opening 55 into a receptacle 56. The two types of drum are thus interchangeable in character, while modified in construction to degrees necessary for the treatment of solids 50 and liquids, and it will, of course, be understood that other modifications within the scope of the invention may be employed as occasion may require for the treatment of various kinds of solids and liquids which 55 may be of an interchangeable character, so that various separatory actions may be performed upon one and the same machine, the speed of the machine and drums being varied in accordance with the character of the 60 material under treatment. The baffle and 65

trough are supported in position by a bracket 57.

I claim as my invention:

1. A centrifugal separator including a central shaft, drums carried and rotatable 70 with said shaft and also rotatable about their own axes, each of said drums having a rifled separating surface, means for driving the central shaft, means for rotating the drums therefrom, and means for varying the 75 angle of the axes of the drums with relation to the central shaft.

2. In a centrifugal separator, a separator drum comprising an upright cylinder, said drum having a spiral riffle upon the inner 80 wall thereof terminating at its upper end in a collecting pocket.

3. A centrifugal separator including a drum rotatable in a fixed orbit and also about its own axis, said drum having a 85 spiral riffle therein provided at the top with a collecting portion, a discharge trough within said drum, means for conducting the material to the drum, and means for operating the drum.

4. A centrifugal separator including a drum rotatable in a fixed orbit and also about its own axis and having a riffle therein, discharge mechanism within the drum and co-operating with the riffle, and means for 95 tilting the drum at an angle to vary the working angle of the riffle.

5. A centrifugal separator including a central shaft, a frame carried by and rotatable with said shaft, a second shaft rotatable 100 about the central shaft, drums carried by the frame for rotation with said frame and central shaft, said drums being also rotatable about their own axes, separating means within the drums, a gear upon the second 105 named shaft, a series of horizontal radial shafts grouped about the central shaft, gears upon the inner ends of said radial shafts meshing with the first named gears, worms carried by said radial shafts, and gears upon 110 the drums meshing therewith.

6. In a centrifugal separator, a separator drum having a spiral riffle upon the inner wall thereof, said riffle terminating at its upper end in a portion formed to provide a collecting pocket.

7. A centrifugal separator including a central shaft, a hollow shaft revolvable about the central shaft, a series of drums carried by and rotatable with the central shaft and also rotatable about their own axes, each of said drums having a rifled separating surface, discharge mechanism within each drum for cooperation with said rifled surface, means for driving the central shaft, means 120 for driving the hollow shaft, and gearing between said hollow shaft and the drums.

8. A centrifugal separator including a central shaft, a frame carried by and rotatable with said shaft, a hollow shaft rotatable 125

about the central shaft, separating drums carried by and rotatable with said frame and also journaled upon the frame to rotate upon their own axes, a feed hopper supported by the frame, a water reservoir carried by the frame, discharge pipes leading from the hopper to the drums, flushing pipes leading through said discharge pipes from the water reservoir to the drums, and means for communicating rotary motion to the central shaft and hollow shaft at different rates of speed.

9. A centrifugal separator including a rotary drum having a spiral flange or riffle therein, discharge mechanism within the drum for coöperation with the rifled portion of the drum, means for bodily rotating said drum in a fixed orbit and also rotating it about its own axis, and means for varying the angle of the drum with respect to its centers of rotation.

10. A centrifugal separator including a drum rotatable in a fixed orbit and also rotatable about its axis, said drum having a spiral riffle therein, discharge mechanism within the drum for coöperation with said riffle, and means for varying the angle of inclination of the rifled surface of the drum with respect to the centers of motion of the drum.

11. A centrifugal separator including a drum rotatable in a fixed orbit and about its axis, said drum having a spiral riffle therein, discharge mechanism within the drum and coöperating with the rifled surface of the drum, and eccentric means for varying the position of the drum and the angle of its rifled surface with respect to its centers of rotation.

12. A centrifugal separator including a drum rotatable in a fixed orbit and about its own axis, said drum having a spiral riffle therein, a combined journal and pivotal support for the drum, eccentric means surrounding the drum for varying the position of the drum and the angle of inclination of its rifled surface with respect to its centers of rotation, and means for driving the drum.

13. A centrifugal separator including a central shaft, a second shaft revoluble about the central shaft, separating drums journaled upon and pivotally supported from the central shaft, said drums being revoluble with said shaft, means for rotating the drums about their axes from the hollow shaft, and means carried by the central shaft for tilting said drums to vary their position and the angle of inclination of their working surfaces with respect to their centers of rotation.

14. A centrifugal separator including a drum rotatable in a fixed path and about its own axis, said drum having a spiral rifled inner surface, a feed device extending into the drum to deliver the material at one side

of the center thereof, a stationary trough arranged within the drum and having a convex surface adjacent said side of the drum and a concave surface adjacent the opposite side of the drum, said drum being adapted 70 to carry the heavier particles from the top of the drum from the first-named to the second-named side and force the same by centrifugal action against the concave side of the trough, and means for rotating the 75 drum.

15. A centrifugal separator including a central shaft, a frame carried by and rotatable with said shaft, a hollow shaft rotatable about the central shaft, separating drums 80 journaled for rotation upon the frame and also pivotally mounted upon said frame so as to be tilted to different working angles, said drums being rotatable with the central shaft and frame, gearing for rotating the 85 drums about their own axes from said hollow shaft, separating means upon the interior of the drums, and means for collecting the separated substances from the drums.

16. In a centrifugal separator, an upright 90 drum rotatable about a vertical axis and having a spiral riffle formed upon the inner wall thereof, said riffle terminating at its upper end in a reentrant portion forming a collecting pocket.

17. In a centrifugal separator, a separator drum comprising an upright cylinder rotatable about a vertical axis and having a spiral riffle formed upon the interior thereof, said riffle terminating at its upper end in a reentrant 100 portion forming a collecting pocket, and means for tilting the drum upon its axis to vary the working angle of the riffle.

18. In a separating machine, a separator drum having a rifled interior surface comprising a spiral thread terminating at its top in a reentrant portion forming a collecting bucket.

19. In a centrifugal separator, a separator drum rotatable about an external axis and 110 also about its own axis, said drum having a rifled interior surface comprising a spiral thread adapted to catch the heavier particles of material and feed the same toward the top of the drum, said thread having at its upper portion a return portion or loop forming a bucket to hold the particles for discharge by centrifugal force when the pocket reaches the side of the drum closest to the center of rotation.

20. In a centrifugal machine, a separator drum rotatable about an external axis and also about its own axis, said drum having a spiral riffle therein provided with a collecting portion, and a trough arranged to collect 125 the material discharged from said collecting portion when said portion reaches a position between the two axes of rotation.

21. In a centrifugal separator, a separating drum rotatable about an external axis 130

- and also about its own axis, said drum being provided with a rifled surface having a terminal collecting portion, means for discharging the material to be treated against the outer side of the inner face of the drum, and a relatively stationary trough within the drum extending longitudinally thereof between the inner and outer surfaces of its rifled portion.
22. In a centrifugal separator, a separating drum rotatable about an external axis and also about its own axis, said drum having a rifled separating surface terminating in a collecting and discharge portion, a conductor entering the top of the drum for discharging the material against the outer side of said rifled surface, a trough extending longitudinally within the drum between the inner and outer portions of its rifled surface, and means for discharging water within the drum and against the respective surfaces.
23. In a centrifugal separator, a separator drum rotatable about an external axis and also about its own axis, and means for varying the axis of the drum with relation to the external axis.
24. In a centrifugal separator, a separator drum rotatable about an external axis and also about its own axis, and means for adjusting the drum to dispose its axis parallel with or at an angle to such external axis.
25. In a centrifugal separating machine, a separator drum rotatable about an external axis and also about its own axis, and eccentric means for adjusting the drum to dispose its axis at different angles to such external axis.
26. In a centrifugal separator, a separator drum rotatable about an external axis and also about its own axis, said drum being pivotally supported at one end, and means operative upon the other end of the drum for adjusting said drum to dispose its axis at different angles to such external axis.
27. In a centrifugal separator, a separator drum rotatable about an external axis and also about its own axis, said drum being pivotally supported at its upper end, and means acting upon the lower end of the drum for swinging said drum upon its pivotal support to adjust its axis at an angle to such external axis.
28. In a centrifugal separator, a separator drum rotatable about an external axis and also about its own axis, said drum being supported for tilting movements, and means for tilting the drum to dispose its axis at different angles to such external axis.
29. In a centrifugal separator, a separator drum rotatable about an external axis and also about its own axis, said drum being pivotally supported to tilt at different angles to the external axis, and an eccentric ring surrounding the drum and adjustable to tilt the drum to dispose its axis at different angles to such external axis.
30. In a centrifugal separator, a central axis, a series of drums grouped about said central axis and revoluble therearound and also revoluble about their own axes, said drums being pivotally supported at their upper ends, and means supporting the lower ends of the drums and adjustable to tilt said drums to dispose their axes at different angles to the central axis.
31. In a centrifugal separator, a central axis, a group of drums extending around and revoluble about said central axis and also about their own axes, said drums having pivotal supports at their upper ends, feed inlets extending into the drums through said pivotal supports, and means for adjusting the drums on the pivotal supports to vary the angle of their axes with relation to the central axis.
32. In a centrifugal separator, a separator drum rotatable about an external axis and also about its own axis, said drum being provided with a rifled separating surface and means for adjusting said drum at different angles with relation to the external axis to vary the working angle of the riffle.
33. In a centrifugal separator, a central shaft, a hollow shaft journaled upon the central shaft, means for driving said shafts, a frame carried by the hollow shaft and including a hopper, an annular series of separator drums arranged below the hopper and having inlets at their upper ends leading from the hopper, a water receptacle extending into the hopper, water supply pipes extending from said receptacle through said inlets and into said separator drums, and means for rotating the drums as they revolve about the central axis on their own axes.
34. In a centrifugal separator, a vertically disposed separator drum rotatable about an outside axis and also about its own axis, said drum having a spiral riffle therein terminating at its upper end in a bucket or collecting portion, a trough or deflector extending longitudinally within the drum in spaced relation to the inner and outer surfaces thereof, and means for conducting the material to be treated into the top of the drum and against the outer side of the rifled surface, whereby on the rotation of the drum the heavy particles will travel upward and be caught in the bucket and discharged against the side of the trough which is closer to the center of rotation of the drum.
35. In a centrifugal separator, a separator drum rotatable about an external axis and also about its own axis, said drum having a spiral riffle arranged therein and provided at its upper end with a bucket or collecting portion, a trough extending downwardly and outwardly within the drum, said trough be-

ing stationary with respect to the drum and disposed edgewise in the direction of rotation of the drum about the external axis, and a feed device entering the top of the drum 5 and disposed between the outer surface of the trough and outer side of the drum, whereby the heavy material will be caused to travel upwardly on the inclined riffle and to be caught in said bucket and discharged

against the relatively inner surface of the 10 trough.

In testimony whereof I affix my signature in presence of two witnesses.
